UNITED STATES PATENT OFFICE.

ALBERT CHENEL, OF NEW BEDFORD, MASSACHUSETTS.

WINDOW-ROD FASTENER.

1,410,459.

Specification of Letters Patent. Patented Mar. 21, 1922.

Application filed February 23, 1921. Serial No. 448,596.

To all whom it may concern:

Be it known that I, ALBERT CHENEL, a citizen of the United States, residing at New Bedford, in the county of Bristol and State 5 of Massachusetts, have invented new and useful Improvements in Window-Rod Fasteners, of which the following is a specification.

In the ordinary construction of window 10 frames, the parting bead for the sashes is let into a groove in the side members or stiles of the frame, and not infrequently the inner and outer sash beads are also let into grooves. In many instances, however, the beads are 15 nailed to the side members of the frame. It frequently becomes necessary to remove these beads, when it is desired to remove the sashes, and as the said beads must be pried away from the frame, injury is inflicted to 20 both the beads and the frame.

It is the object of the present invention to produce a means whereby the beads may be effectively sustained on the frame without the employment of nails or the like, and likewise be readily removed therefrom when occasion requires without imparting injury to either the beads or the frame.

The foregoing, and other objects which will appear as the nature of the invention is 30 better understood, may be accomplished by a simple construction, combination and arrangement of parts, such as is disclosed by the drawings which accompany and form part of this application.

35 In the drawings:—

Figure 1 is a perspective view of a portion of a window frame showing the beads attached thereto in accordance with this invention.

40 Figure 2 is a sectional view, on an enlarged scale, and approximately on the line 2—2 of Figure 1.

Figure 3 is a view of the elements constituting the attaching means.

The side member of an ordinary window 45 frame is indicated, in the drawings, by the numeral 1. The parting bead is indicated by the numeral 2, the inner bead by the numeral 3 and the outer bead by the numeral 4. The parting bead 2 and the outer bead 4 50 are let into grooves in the side member of the window frame.

In the sides of the frame in the center of each of the grooves, for the beads, I screw 55 therein socket members 5. The sockets have their entering ends pointed, as at 6, and their opposite or outer ends kerfed, as at 7. The bore of each of the sockets is threaded and the sockets are, of course, provided on their outer surfaces with threads. The kerf is 60 designed to receive a screw driver or like instrument whereby the sockets may be screwed into the member 1.

Each of the beads, 3, 2 and 4, in a line with the respective sockets have openings 65 therethrough, the said openings being reinforced by metallic sleeves 8. Passing through these sleeves 8 are the threaded shanks 9 of headed members 10, the said shanks entering the threaded bores of the 70 sockets, and contacting with the outer flanged ends of the sleeves 8 bind the beads in their respective grooves and secure the same on the side of the frame.

Having thus described the invention, I 75 claim:—

A device for the purpose set forth, comprising a socket member having a pointed end and having exterior threads for the length thereof, said socket having its widened 80 end kerfed and its bore threaded, a flanged sleeve designed to contact with the widened end of the socket, and a headed screw passing through the sleeve and threadedly engaging the bore of the socket. 85

In testimony whereof I affix my signature.

ALBERT CHENEL.
